HOOD FOR AN ELECTRICAL CONNECTOR OR SIMILAR ARTICLE

Bengt J. Johanson, Des Plaines, Ill., assignor to United-Carr Fastener Corporation, Boston, Mass., a corporation of Delaware

Filed June 28, 1963, Ser. No. 75,582

Term of patent 14 years

(Cl. D26—1)

Fig 1

Fig. 2

Fig 4

Fig 3

FIG. 1 is a front elevational view of the hood for an electrical connector or similar article, showing my new design;

FIG. 2 is a side elevational view of the same as seen from the right in FIG. 1;

FIG. 3 is a side elevational view thereof as seen from the left in FIG. 1; and

FIG. 4 is a top plan view thereof.

The essential features of my design reside in those portions shown in full lines in the drawing.

I claim:

The ornamental design for a hood for an electrical connector or similar article, substantially as shown and described.
